UNITED STATES PATENT OFFICE.

RUSSELL D. BELDEN, OF BUFFALO, NEW YORK, ASSIGNOR TO DUNLOP TIRE AND RUBBER CORPORATION OF AMERICA, OF BUFFALO, NEW YORK, A CORPORATION OF NEW YORK.

DESIGN FOR A TIRE TREAD.

Application filed December 19, 1923. Serial No. 8,089. Term of patent 14 years.

To all whom it may concern:

Be it known that I, RUSSELL D. BELDEN, a citizen of the United States, and resident of Buffalo, New York, have invented a new, original, and ornamental Design for Tire Treads, of which the following is a specification, reference being had to the accompanying drawing, forming a part thereof.

Fig. 1 is a sectional perspective view;

Fig. 2 is a sectional plan view; and Fig. 3 is a cross-sectional view of a tire showing my new design.

I claim:

The ornamental design for a tire tread as shown.

In witness whereof, I have hereunto signed my name.

RUSSELL D. BELDEN.
